G. H. VINETTE.
CUSHION SPRING.

APPLICATION FILED DEC. 31, 1915. RENEWED AUG. 23, 1918.

1,281,440.

Patented Oct. 15, 1918.

UNITED STATES PATENT OFFICE.

GEORGE H. VINETTE, OF DETROIT, MICHIGAN.

CUSHION-SPRING.

1,281,440.

Specification of Letters Patent. Patented Oct. 15, 1918.

Application filed December 31, 1915, Serial No. 69,532. Renewed August 23, 1918. Serial No. 251,179.

To all whom it may concern:

Be it known that I, GEORGE H. VINETTE, a citizen of the United States, and residing at Detroit, in the county of Wayne and 5 State of Michigan, have invented a new and Improved Cushion-Spring, of which the following is a specification.

The object of the present invention is to provide a cushion spring construction such, 10 for example, as used in automobile seats, wherein both the initial expense for material is reduced and the parts may be more rapidly assembled than heretofore.

The invention consists, primarily, in a 15 series of clips arranged at intervals along the usual circumferential base members or border wires and extending upwardly therefrom to embrace the lower edge of the skirting. The invention also consists in clips 20 of this general nature having tangs bent over the lower turn of the usual helical springs, whereby the springs, circumferential member and skirting may be secured in proper relation to one another; also in clips 25 of the nature first stated having tangs for securing the usual cross wires to the border wires. The invention further consists in the details of construction shown, described and claimed.

30 In the drawings, Figure 1 is a fragmentary vertical section of a seat bottom wherein in my invention is embodied. Fig. 2 is a perspective view of the lower corner of the spring, parts being broken away, showing 35 more clearly the manner of attaching the web or skirt to the border wire. Figs. 3, 4 and 5 are similar views of one side, showing modified clips. Fig. 6 illustrates the clip shown in Fig. 2 before it is closed upon 40 the border wire and skirt; and Fig. 7 is a similar view of a modified form of clip. Fig. 8 is a fragmentary perspective view, showing a different border member. Fig. 9 is a perspective view of a clip whereby the 45 skirt, the border wire and one of the helical springs are secured together. Fig. 10 is a similar view of a clip for securing the border wire, cross wires and skirting together. Figs. 11 and 12 are plan views, 50 respectively, of the blanks from which the clips shown in Figs. 9 and 10 are formed. Fig. 13 is a fragmentary perspective view of a modified construction.

Similar reference characters refer to like 55 parts throughout the several views.

Referring particularly to Figs. 1, 2 and 6, 1 indicates the usual circumferential member or border wire, between which cross wires 2 extend at intervals from side to side. These cross wires support helical 60 springs 3 upon which the upholstering 4 rests in a well known manner; and depending from the marginal edges of the upholstering is a flexible circumferential skirting 5, preferably of leather or fabric, the lower 65 edge of which is turned back upon itself at 6 and preferably incloses a cord or wire 8, thus forming a bead. It will be understood that the portion 6 is sewed or otherwise secured to the body portion of the skirting in 70 any desired manner.

When the parts are to be assembled, the 75 spring is inverted from the position shown in Fig. 1, and a series of clips (each of which preferably includes a long side portion or jaw 10 and a short side portion or jaw 11, the latter of which terminates in an inturned edge or rib 12 that is normally spaced somewhat from the side 10) are dropped over the circumferential member or 80 border wire. The skirting is then raised into the space between the sides or jaws 10—11 of the clip, and by means of a proper tool the side 11 is bent in toward the side 10 until the rib 12 snugly engages under the bead of 85 the skirting. It will be noticed that the long side or jaw 10 is on the outside of the skirting and lies substantially parallel thereto. It also preferably extends somewhat beyond the rib 12, whereby the wear on the fabric 90 or skirting is lessened. The clips, when formed of thin sheet metal, are exceedingly inexpensive.

In some instances the rib 12 may be replaced by teeth 13 (see Fig. 7); and, as 95 shown in Fig. 3, the bending tool may be so formed as to crimp the clips slightly at the points 14—15 between the border wire and the bead. Instead of the sheet metal clips heretofore described, wire clips (Fig. 4) 100 may be used. These clips are preferably formed from a single piece of wire having a longitudinal portion 16 and end portions 18 at substantially right angles thereto, both of which lie in a plane parallel to the skirting 5 and correspond to the side or jaw 10. The portions 18 are extended over the border wire and bent back upon themselves under the bead as indicated at 19. By slightly changing the shape of the clip, it may be 110

adapted to connect the skirting to circumferential members 21 of channel cross section, as shown in Fig. 8. In this case, the lower turn 22 of the helical springs may be 5 inserted between the flanges of the channel member 21 and the latter bent together to secure it firmly in position.

The clip shown in Fig. 5 includes the jaws 10 and 11—12 heretofore described, and is 10 extended at each end to form jaws or clip elements 23 and 24, which are bent in the opposite direction to grip the border wire 1. By slightly extending the outer ends of the jaws or clip elements which correspond to 15 those marked 24 (Fig. 5), flaring elements 28 are formed, between which and the jaws 23 the lower turn 29 of the helical springs, together with the border wire 1, may be gripped (Fig. 9). The last mentioned clip 20 is readily formed from a blank slotted as shown in Fig. 11, the dashed lines therein indicating the lines about which the parts are to be bent. As is obvious, the border wire 25 and spring may be located below the upper portion of the jaws 10—11, and in this event the elements 28—29 would be bent in the opposite direction from that shown in Fig. 9.

In the modification which appears in Fig. 10, the elements 28 are replaced by elements 30 which extend at substantially right angles to the border wire 1 and have their outer margins 31 bent up around the cross wire 32 (each end of which is preferably of U-shape and includes a portion 33 in the same 35 plane and parallel with the adjacent portion of the border wire). The clip is readily formed from a blank slotted as shown in Fig. 12 by bending about the dashed lines.

Referring now to Fig. 13, the circumferential member comprises a base flange 35 and a circumferential flange 36. The former has resting thereon the lower turn of the helical springs 3, these springs preferably being secured in position by tangs 38 45 formed by slitting and bending the edge of the flange; and the skirting 5 passes down inside of the flange 36 and is retained in position by tangs 39 struck from the flange 35. These tangs embrace the bead of the skirting 50 and force it against the inner face of the flange—a construction which obviates direct wear upon the skirting to a large degree.

It is clear that the details of the various parts may be changed widely without deviating from the spirit of my invention, and I do not, therefore, wish to be limited otherwise than as indicated by the subjoined claims.

I claim:—

60 1. A spring construction comprising a circumferential base member, springs, upholstering supported on the springs, a flexible skirting depending from the upholstering and extending substantially to the base member, said skirting being located wholly

on the side of the base member adjacent the upholstering, and short independent metal clips passing around the side of the base member opposite to the skirting and embracing the base member and the edge of the 70 skirting at intervals without passing through said skirting whereby the latter is secured firmly in position.

2. A spring construction comprising a circumferential base member arranged in a 75 plane, helical springs projecting from the plane of the base member, upholstering covering the outer ends of the springs, a flexible skirting extending from the upholstering in a plane at substantially right angles to 80 the plane of the base member, said skirting terminating on the side of the base member nearest the upholstering, and short independent sheet metal clips passing around the side of the base member opposite to the skirting 85 embracing the base member and the edge of the skirting without passing through said skirting.

3. A spring construction comprising a circumferential base member arranged in a 90 plane, helical springs projecting from the plane of the base member, upholstering covering the outer ends of the springs, a flexible skirting extending from the upholstering in a plane at substantially right angles to 95 the plane of the base member, said skirting terminating on the side of the base member nearest the upholstering, and short sheet metal clips embracing the base member and the edge of the skirting, each of said clips 100 including a relatively long jaw that lies against the outside of the skirting and a relatively short jaw having its end bent outwardly and engaging the inner side of the skirting.

4. A spring construction comprising a circumferential base member arranged in a plane, helical springs projecting from the plane of the base member, upholstering covering the outer ends of the springs, a flexible 110 skirting extending from the upholstering in a plane at substantially right angles to the plane of the base member, said skirting terminating in a bead located on the side of the base member nearest the upholstering, and substantially vertically above the base member, and a separate sheet metal member embracing the base member and the bead, said member including a relatively long jaw that lies against the outside of the skirting and a 115 relatively short jaw having its end bent outwardly and engaging the inner side of the skirting.

5. A spring construction comprising a circumferential base member arranged in a 125 plane, helical springs projecting from the plane of the base member, upholstering covering the outer ends of the springs, a flexible skirting extending from the upholstering in a plane at substantially right angles to the 130

plane of the base member, said skirting terminating in a bead located on the side of the base member nearest the upholstering, and substantially vertically above the base member, and a separate sheet metal member embracing the base member and the bead of the skirting, said member including a portion that lies against the outside of the skirting and another portion having its edge bent outwardly toward the first named portion to engage the bead.

6. A spring construction comprising a circumferential base member arranged in a plane, a cross wire joining opposite sides of the base member, a helical spring projecting from the cross wire, upholstering covering the outer end of the spring, a flexible skirting extending from the upholstering in a plane at substantially right angles 20 to the plane of the base member, said skirting terminating on the side of the base member nearest the upholstering, and short separate sheet metal clips embracing the base member and the edge of the skirting, said 25 clips also including a portion which embraces the adjacent cross wire.

7. A spring construction comprising a circumferential base member arranged in a plane, a cross wire joining opposite sides of the base member, a helical spring projecting from the plane of the base member, upholstering covering the outer end of the spring, a flexible skirting extending from the upholstering in a plane at substantially right 30 angles to the plane of the base member, said skirting terminating on the side of the base member nearest the upholstering, and short separate sheet metal clips embracing the base member and the edge of the skirting, 35 said cross wire and said spring constituting two members, said clips also including a por-

tion that embraces one of the last mentioned members.

8. A spring construction comprising a plurality of helical springs projecting from a common base, upholstering covering the outer ends of the springs, a skirting extending from the upholstering toward the base and terminating on the side thereof next the upholstering, and means for securing the edge of the skirting in position, said means including a portion that embraces the skirting on the side remote from the springs and another portion that embraces the skirting on the side opposite the first named portion, 55 said first named portion extending farther toward the upholstering than the second named portion whereby said edge of the skirting is maintained in vertical alinement with the outer face of the base. 60

9. A spring construction comprising a plurality of helical springs projecting from a common base, upholstering covering the outer ends of the springs, a skirting extending from the upholstering toward the base 65 and terminating on the side thereof next the upholstering, said skirting having a beaded edge, and means for securing the edge of the skirting in position, said means including a portion that embraces the skirting on 70 the side remote from the springs and another portion that embraces the beaded edge on the side opposite the first named portion, said first named portion extending farther toward the upholstering than the second 75 named portion whereby said edge of the skirting is maintained in vertical alinement with the outer face of the base.

In testimony whereof I sign this specification.

GEORGE H. VINETTE.
